(57) **CLAIM**

The ornamental design for a selectable seal deck plug having two different O-ring grooves, as shown and described.

DESCRIPTION

FIG. 1 is a side elevational view of the selectable seal deck plug having two different O-ring grooves showing my new design. All side views are identical;

FIG. 2 is a close up, enlarged to scale view of the lower portion, partial side elevational view, of the deck plug, showing the different o-ring groove depths;

FIG. 3 is a top plan view;

FIG. 4 is a bottom plan view of my claimed design; and, FIG. 5 is top perspective view of the selectable seal deck plug having two different O-ring grooves.

The broken lines represent the boundaries of the enlarged partial view of FIG. 2 and form no part of the claimed design.

1 Claim, 3 Drawing Sheets
